UNITED STATES PATENT OFFICE.

KARL BARTH, OF ESSEN-ON-THE-RUHR, GERMANY, ASSIGNOR TO FRIED. KRUPP AKTIENGESELLSCHAFT, OF ESSEN-ON-THE-RUHR, GERMANY.

SELF-UNLOADING VESSEL.

1,128,572.

Specification of Letters Patent. Patented Feb. 16, 1915.

Application filed April 25, 1914. Serial No. 834,383.

To all whom it may concern:

Be it known that I, KARL BARTH, residing at Essen-on-the-Ruhr, Germany, a citizen of the German Empire, have invented a certain new and useful Improvement in Self-Unloading Vessels, of which the following is a specification.

The present invention relates to self unloading vessels of the character shown and described in my co-pending application Serial No. 796,272, filed October 20, 1913, and has for its object to provide a device, whereby all of the moving parts, during the transfer of the movable bottom from unloading to loading position are placed approximately in indifferent equilibrium, in order to limit to a minimum the power consumption necessary to move the bottom.

One embodiment representing a self unloading car is illustrated in the accompanying drawing, where

Figure 1 shows a cross section of the wagon in loading position, and Fig. 2 a similar view of the car in unloading position.

The self unloading car is, in general, constructed as the car described in my above named application.

Reference character A denotes the under-frame of the car, A¹ the two end walls, a³ the stay rod, serving as journal for the side wall C³, which has no hinge connection with the bottom B, a⁵ a beam supporting the bottom in its unloading position and C the side wall hinged to the bottom, the side wall C³ being provided with hooks c⁴.

The bottom B is mounted to oscillate on the under-frame A by means of links D and D¹, of U-shaped transverse section, each two crossing each other and being of the same length and arranged at suitable intervals along the bottom. The intersecting places of the links D and D¹, the upper fulcrum points of which are much closer together than the lower ones, are situated between the vertical, longitudinal middle-plane of the car and the side wall C, when the car is in loading position, see Fig. 1, these intersecting places of the links constituting the momentary axis of revolution of the bottom B. At its lower edge, the side wall C is provided with several handles c¹, and at its two upper corners and rigidly secured thereto with two shoes c², by means of which the side C grips over the abutment

faces on the upper ends of the side rails a² of the end walls A¹, when the car is in loading position, Fig. 1, thereby supporting itself and also contributing to the support of the end walls A¹. A guide bar G, for each of the shoes c², constitutes a link connection with each of two guide bearings a⁴ secured at the upper edge of the end walls A¹. The length of the bars G and the position of their axes of revolution has been so selected that the side wall C, during the tilting of the bottom B will be carried parallel in approximately perpendicular position. The side wall C³ may be swung around the rod a³ by means of a crank shaft gearing provided with a hand lever H.

In order to unload the car, the hand lever H is turned toward the left, so that the side wall C³ swings outward, the hooks c⁴ releasing the bottom B, and the latter, on account of the weight of the load acting to one side, tilting until it strikes the beam a⁵. The side wall C will at the same time be raised without materially changing its vertical position. Simultaneously a longitudinal axis, immovable relative to the bottom B, and situated about midway between the journals for the rods D and D¹ on the bottom, is displaced in approximately horizontal direction.

If s denotes the center of gravity of the bottom B, s¹ the center of gravity of the side wall C and s² the common center of gravity of the movable system comprising the bottom B and the side wall C, and supposing further that the distance between s and s² is called S and the distance between s¹ and s² is called Z, the ratio $\frac{Z}{S}$ has obviously then a constant value equal to the ratio between the weights of the bottom B and the side wall C, this ratio in the following being denoted by the character k. Supposing now, that the point p—at which point the axis of the journal connecting the bottom B with the wall C intersects with the vertical plane passing through the straight line s—s²—s¹— is connected with the points s¹ and s, and that a point q is so fixed on the line p—s, that the ratio

$$\frac{X}{Y} = k,$$

when the distance between q and p is called X and that between q and s is called Y, then

the line $q-s^2$ will always be parallel with the line $p-s^1$, and have a constant value of

$$\frac{P}{k+1}$$

5 where P is the length of $p-s^1$. As the line $p-s^1$ always has the same direction in consequence of the side wall C being parallelly displaced, the same also applies to the line 10 $q-s^2$. The common center of gravity s^2 has therefore an unchangeable distance, in a direction which always remains the same from the point q which is fixed relative to the bottom B. If, as has been assumed in 15 the described embodiment, the point q is situated in the above mentioned longitudinal axis of the bottom, which axis travels approximately in horizontal direction, the point q will then move in an approximately 20 horizontal line, during the tilting movement of the bottom. Consequently, the common center of gravity s^2 must obviously also move in an approximately horizontal line because it possesses a constant distance from 25 the point q in a direction which always remains the same. The movable system, formed by the bottom and the side wall C, will therefore be in approximately indifferent equilibrium with each different position 30 of the bottom. The influence of the other movable parts on the equilibrium of the entire movable system composed of the parts B, C, G, D, D¹, is only slight, and may moreover be easily compensated for by a 35 slight displacement to one side of the connecting rods D and D¹.

In consequence of the parallel transfer of the side wall C, it will therefore be attained with great exactitude that the entire movable system is in approximately indifferent equilibrium with each different position of the bottom. Without any appreciable exertion, the bottom may therefore be swung back into loading position, Fig. 1, from unloading position, Fig. 2, by pulling on the handles c¹. This position is attained at that moment, when the downward swinging side wall C grips with its shoes c² over the abutment faces on the upper ends of the side bars a², thus being prevented from continued downward oscillation. By turning the hand lever H, the side wall C³ is thereupon swung back into its perpendicular final position, when it grips with its hook c⁴ underneath the bottom B, securing the latter from unintentional opening movement.

As the axis of revolution of the bottom B, which is determined by the crossing points of the connecting rods D and D¹, is displaced toward the unloading side during the 60 opening movement, the side wall C executes

a greater transverse movement toward the unloading side, than would be the case with fixed axis of revolution of the bottom. This has the particular advantage that the gliding down of the load will be hastened.

I claim:—

1. A self unloading vessel comprising a frame, a receptacle of rectangular cross section when in loading position, said receptacle having two end walls rigidly mounted on said frame and a bottom adapted to swing about an axis parallel to the central longitudinal axis of the receptacle and lying between this longitudinal axis and one of the side walls of the receptacle, this side wall being hinged to said bottom, and connecting members for said hinged side wall being so arranged that said side wall when in unloading position is at least approximately parallel to itself when in loading position.

70 2. A self unloading vessel comprising a frame and a receptacle; said receptacle having movable bottom and sides; one of the sides being hinged to the bottom; means connecting said bottom with said frame, said means causing the axis of oscillation of said bottom to travel toward the discharge side when unloading.

75 3. A self unloading vessel comprising a frame and a receptacle; said receptacle having movable bottom and sides; one of the sides being hinged to the bottom, connecting members for said hinged side being so arranged that said side when in unloading position is at least approximately parallel to itself when in loading position; means connecting said bottom with said frame, said means causing the axis of oscillation 100 of said bottom to travel toward the discharge side when unloading.

80 4. A self unloading vessel comprising a frame and a receptacle; said receptacle having movable bottom and sides; one of the sides being hinged to the bottom; crossed connecting rods having hinged connection both with said bottom and said frame, the fulcrum points on the bottom being so much closer together than the fulcrum points on 105 the frame, that a point centrally situated between said bottom fulcrum points, travels in an approximately horizontal direction during the transfer of the bottom from the loading to the unloading position.

85 The foregoing specification signed at Barmen, Germany, this 4th day of April, 1914.

KARL BARTH. [L. s.]
